WHEEL FLANGE LUBRICATOR

Howard R. Whiting, Battle Creek, Mich.

Application February 7, 1947, Serial No. 726,994

4 Claims. (Cl. 184—3)

1

This invention relates to new and useful improvements in wheel flange lubricators of which the following is a specification.

The primary object of this invention resides in the provision of a lubricating device which retains a bar of lubricant in contact with the flange of a locomotive wheel until said lubricant is consumed wherein the device is conveniently removed, cleaned and refilled with additional lubricant.

Another object of this invention is the provision of a lubricator as set forth which applies lubricant to only the flange of the wheel and eliminates the possibility of the tread of the wheel becoming lubricated and causing slippage and loss in efficiency as often occurs with use of liquid lubricants.

Another and still further object of this invention is the provision of a lubricator for wheel flanges which is effective and reliable in use and affords great conveniences in the application of bar lubricants.

Still another object of this invention resides in the provision of a lubricator of the character described which is of a simple, durable, and extremely inexpensive design and construction.

Still further improvements and advantages of this invention will readily appear to those skilled in the art when the following description is read in the light of the accompanying drawings in which:

Fig. 1 is a side elevation of the assembled lubricator.

Fig. 2 is a horizontal section taken on line 2—2 of Fig. 1.

Fig. 3 is a vertical section taken on line 3—3 of Fig. 2.

Fig. 4 is a partial vertical section taken on line 4—4 of Fig. 1.

Referring now to the accompanying drawings which illustrated the preferred embodiment of this invention and in which like numerals indicate similar parts throughout A designates an elongated cylindrical housing open at both ends thereof and provided with external threads 1 for a spaced distance inward one end thereof.

An internally threaded cap plug 2 is provided with an extended boss 3 in the center thereof in which is slidably retained an elongated shaft 4 provided at one end with a circular plate 5 adapted to slide within said housing, when said plug is secured about the threaded end thereof, and a curved hollow housing 6 is formed at the second external end thereof with the mouths of said housing disposed toward the cap plug.

2

A second circular plate 7, of the same size as plate 5, provided with a curved flange 8 thereon is adapted to receive one end of a coil spring 9 about the curved flange in a snap fit, and said plate is freely inserted into the open end of the cylinder A spring first so that the second end of the spring 9 abuts with the plate 5.

A bar lubricant 10, such as graphite or the like, of the same diameter as the cylinder A is slidably inserted thereinto to abut with the plate 7 and is normally retained in an extended position therefrom by the resilience of the coil spring 9.

The cylinder A is provided with an eye hook 11 extending from one side thereof intermediate its length, and an extended ear 12 diametrically opposite, both of said projections being disposed beneath one of the two open mouths of the curved housing 6. A link chain 13 is secured in the eye hook 11 and passes upwardly through the curved housing 6 and outwardly through the second mouth thereof to a position adjacent the ear 12 where it is adapted to be removably secured in a slot 14 therein by sliding one link of the chain 25 into the slot which is prevented from movement by the adjacent links thus locking the chain in said position and retaining the sliding rod 4 against extension from the plug cap beyond the limit of the chain setting. Thus a means for controlling the distance of the position of plate 5 within the cylinder is provided and thereby a selectively operated control for the feeding of the lubricant from the cylinder is also provided.

An enlarged split cylinder B adapted to be selectively slidably positioned on the cylinder A and secured in place by ears 15 provided on either side of the split which are selectively tightened by a threaded stud 16 interconnecting said ears.

This cylinder B carries an extension arm C 40 which is provided with means for securing said cylinder and lubricator in place in a proper position adjacent the flange of a wheel.

It may be readily seen that the cylinder B is 45 slidable along the length of the cylinder A to facilitate the positioning of the lubricator in its proper position, and that the lubricant bar 10 will feed automatically through the open end of the cylinder A against the flange under the resilient force of the spring 9, and also that the tension of the spring may be increased with a decrease in the length of the lubricant bar by taking up on the chain 13 and forcing the shaft 4 inward the cylinder A.

Having thus described and explained this in-

vention and with full belief that modifications in size, materials and general characteristics would not constitute departure from the spirit of this invention what I desire to claim in Letters Patent is:

1. A wheel flange lubricator of the character described comprising, an elongated cylindrical casing threaded at one end, a cap plug threadedly secured about the threaded end of said casing, an extended hollow boss formed on said cap, an elongated shaft slidably mounted in said boss, a circular plate carried by the inner end of said shaft and adapted to slide within said casing, a coil spring carried in said casing in abutment with said plate, a bar lubricant slidably carried in said casing and normally retained in an extended position from the second end of said casing, and means for adjusting the position of said shaft comprising, a curved hollow housing positioned transversely of the outer end of said shaft, an eye hook on said casing, a slotted ear on said casing diametrically opposite said eye hook, and a link chain secured at one end to said eye hook, said link chain passing through said housing and adapted to be adjustably secured to said slotted ear.

2. A wheel flange lubricator of the character described comprising, an elongated cylindrical casing threaded externally at one end, an internally-threaded cap plug secured about and enclosing the threaded end, an extended boss formed with said cap, an elongated shaft slidably mounted in said boss, a circular plate carried transversely of the inner end of said shaft and slidably within said casing, a second circular plate slidably positioned in said casing, a coil spring positioned in said casing between said circular plates, a bar lubricant slidably carried in said casing in abutment with said second plate and retained in an extended position from the second end of said casing, and means for adjusting the position of said shaft comprising, a curved hollow housing positioned transversely of the outer end of said shaft, an eye hook on said casing, a slotted ear on said casing diametrically opposite said eye hook, and a link chain secured at one end to said eye hook, said chain passing through

4
said housing and adapted to be adjustably secured to said slotted ear.

3. A wheel flange lubricator comprising, a casing, a bar lubricant slidably housed in said casing extending from one end thereof, means in said casing for retaining said lubricant in said extended position, said means including a shaft slidably positioned in said casing extending beyond the second end thereof, and adjusting means for 10 said shaft comprising, a curved hollow housing positioned transversely of the outer end of said shaft, an eye hook on said casing, a slotted ear on said casing, and a link chain secured at one end to said eye hook, said chain passing through said housing, and adapted to be adjustably secured to said slotted ear.

4. A wheel flange lubricator comprising, a tubular casing, a shaft slidably mounted in said casing and extending from one end thereof, a bar lubricant slidably carried in said casing and normally retained in an extended position from the second end of said casing, a resilient member in said casing operatively positioned between said shaft and said bar lubricant, and means for adjusting the position of said shaft in said casing, said means including a housing on said shaft adapted to receive a chain for slidable movement therein, an eye hook on one side of said casing, a slotted ear on the opposite side of said casing, and a chain secured at one end to said eye hook, said chain passing through said housing and adapted to be adjustably secured to said slotted ear.
